UNITED STATES PATENT OFFICE.

NORMAN L. DOOTSON, OF SAN FRANCISCO, CALIFORNIA.

HATBAND.

Application filed October 27, 1926. Serial No. 144,478.

This invention relates to improved hat bands and has more particular reference to one which is reversible, both sides of the band being properly ornamented and colored to permit changing of the band from one side to the other.

Briefly, the band has its adjacent ends constructed to form an imitation bow, means being provided for holding said ends together with either side exposed to view.

The structural features permitting the formation of such bow and allowing such reversibility will become apparent from the description following and accompanying drawings.

In the accompanying drawings:—

Figure 1 is a side elevation showing the band in position on a hat.

Fig. 2 is an enlarged elevational view of the band ends showing the same separated.

Fig. 3 is an enlarged top plan view showing the manner in which the ends of the band are associated with the crown of the hat.

Fig. 4 is an exaggerated cross section on the line 4—4 of Fig. 2.

Referring to the drawings in detail, it will be seen that the band is of somewhat ordinary general form, the ends being represented by the reference characters 1 and 2 respectively.

Carried by the end 1 are two equal plies of material 3 shaped so as to provide one-half or one wing of a bow. Surrounding the end portions of these plies of the material, is a strip 4 which is passed around the U-shaped fastening pin 5 as shown plainly in Fig. 3.

Carried by the terminal portion 9 of the end portion 2 is one set of elements of a separable fastener. For instance, each element is in the form of a flanged sleeve 6 (see Fig. 4) having double sockets 7 for reception of the headed studs 8 carried by the terminal piece 4 of the end portion 1. The piece 9 is attached to the end portion 2 through the medium of connecting pieces 10. These pieces 10 are shaped to correspond to the aforesaid plies 3.

In practice the band is placed around the crown 11 of the hat, in a customary manner, the end 1 being secured to the pin 5. Then the terminal piece 9 is brought into over-

lapping relation with the end piece 4 and the fasteners are secured together. This simultaneously connects the ends of the band and makes the imitation bow. However, as before stated, with this arrangement, either side of the band may be disposed to view, thus rendering it reversible.

Consequently, when one side becomes soiled, the band can be reversed to bring the other side to view. It is believed that by considering the description in connection with the drawings, a clear understanding of the construction, use and advantages will be had. Consequently a more lengthy description is thought unnecessary.

In connection with the structure, it will be noted that it becomes unnecessary to disconnect the end 1 of the band from the U-shaped staple or pin 5. It is only necessary in order to reverse the band, to employ this pin as a hinge. For instance, by disconnecting the end 2, and swinging it completely around the hat, the band end 1 will assume a position on the opposite side of the pin and the band 2 will replace it. As the fastening elements are on both sides of the band, they may be connected together again. Moreover, as the ends of the band are fashioned alike, they will come together to make the imitation bow.

Having thus described my invention, what I claim as new is:—

1. In combination, a hat, a reversible band surrounding the crown of the same, the ends being separable and provided with cooperating fastening elements, and a pivot pin carried by and arranged in spaced relation to said crown and with which one end of the band is hingedly connected, whereby the band may be reversed on the pin.

2. In combination, a hat having a crown, a U-shaped pin carried by and permanently connected with the crown and having an upright portion spaced from the outer side of the crown, a reversible band, the ends of which are provided with cooperating fastening elements and one of which is separable from the other, and a looped terminal key carried by one end of the band and receiving in its bight the upright portion of said pin.

3. In combination, a hat having a crown,

a reversible band with separable ends and having spaced from said ends bow simulating portions, cooperating fastening elements on the ends of the band, and pivot means connecting one end of the band permanently to the crown; said end of the band being swingable on said pivot pin for the

reversal of the band, and the said cooperating fastening elements being provided at opposite sides of the end portions of the ¹⁰ band.

In testimony whereof I affix my signature.

NORMAN L. DOOTSON.
